H. PRIES.
REFRIGERATOR CAR.
APPLICATION FILED MAR. 20, 1911.

1,007,485.

Patented Oct. 31, 1911.

UNITED STATES PATENT OFFICE.

HERMAN PRIES, OF MICHIGAN CITY, INDIANA.

REFRIGERATOR-CAR.

1,007,485.

Specification of Letters Patent. Patented Oct. 31, 1911.

Application filed March 20, 1911. Serial No. 615,733.

To all whom it may concern:

Be it known that I, HERMAN PRIES, a citizen of the United States, and resident of Michigan City, county of Laporte, and State of Indiana, have invented certain new and useful Improvements in Refrigerator-Cars, of which the following is a specification, and which are illustrated in the accompanying drawings, forming a part thereof.

10 The invention relates to means for effecting the drainage of the ice tanks of refrigerator cars; its object being to provide a valve controlled drainage outlet so arranged that the cover to the tank can be applied to its 15 seat only when the valve is closed.

15 The practice heretofore prevailing has been to permit the free discharge of water from the tanks when a certain level has been reached by the melting of the ice. As a 20 consequence there has been a continuous dripping of the salt-impregnated water in transit, to the detriment of the track and its appurtenances.

25 By the introduction of a cock in the drainage outlet and the arrangement of its handle as now proposed, the drainage will occur only when the tank is opened and the valve turned. This will ordinarily be done only in connection with the icing of the tank, and 30 consequently at a place where the water discharge can be conveniently conveyed away without detriment to the track.

35 The invention further prevents carelessness on the part of employees, compelling them to close the valve before sealing the tank.

40 With these objects in view the invention consists in a structure such as is hereinafter described and illustrated in the accompanying drawings, in which the valve stem is of sufficient length to project above the top of the tank and is jointed to permit the upper end to be folded to lie below the tank cover, the extension above the joint, however, being of such length with reference to the width of the tank that it can not be folded to horizontal position except when the valve 45 is closed.

45 In the drawings—Figure 1 is a detail 50 transverse section of a car through the ice tanks; Fig. 2 is a detail plan view of a portion of the car showing the tops of the ice tanks; Fig. 3 is a detail perspective view of the valve stem; and Fig. 4 is a plan section 55 of the drainage cock.

The body of the car is represented at 10,

and there is shown two pairs of ice tanks 11, 12, and 13, 14, arranged transversely of the car. The tanks of each pair are spaced apart, as shown, and are connected by a 60 drainage pipe 15, having a discharge nipple 16 within which is located a two-way valve 17. The stem 18 of the valve extends upwardly above the top of the car, and is jointed, as shown at 19, at the top of the tanks 65 and below the level of the lid 20 which covers both tanks of the pair.

That portion 21 of the valve stem which is above the joint 19 is of such length and is so disposed that it cannot be folded down 70 to horizontal position below the lid 20 except when the valve is closed. This is accomplished by relatively so positioning the valve and stem that the joint 19 of the latter flexes transversely of the tank when 75 the valve is open and longitudinally thereof when the valve is closed; the length of the upper portion of the stem is such that when folded transversely of the tank it will extend beyond the cover seat, thereby preventing 80 the adjustment of the cover, but when folded longitudinally of the tank it will not reach to the end of the cover seat. Furthermore, the stem is provided with a handle or grip piece 22 or 23, which is so directed that 85 it lies in horizontal position when the stem is folded down only when the valve is closed. This disposition of the handle or grip member would effectively prevent the placing of the cover even if the upper section of the 90 stem were so short that it would fold below the cover seat when transverse of the tank. This form of grip member has the further advantage that when the cover is opened it forms an obstruction to the entrance of ice 95 until raised, thereby calling the attention of the attendant to the fact that the drain cock is not open. Either form of grip member, that shown at 22, which consists of a cross-bar at the upper end of the stem, or 100 that shown at 23, which is a mere lateral projection of the stem in one direction, may be used.

I claim as my invention—

1. In a car, in combination, an ice tank 105 having an oblong opening at its top, a lid for covering such opening, a drain cock for the tank, a stem for the cock extending above the tank and being jointed below the cover seat, the length of the stem above the 110 joint being greater than the distance from the joint to the side of the tank opening

and less than the distance from the joint to the end of the tank opening, the valve and stem being so related that the valve is closed when the stem folds lengthwise of the tank opening.

5 2. In a car, in combination, an ice tank, a cover therefor, a drain cock for the tank, a jointed stem for the drain cock, such stem extending above the cover seat, its upper 10 end being adapted to fold below the cover seat only when the drain cock is closed.

3. In a car, in combination, an ice tank having an oblong opening at its top, a lid for covering such opening, a drain cock for 15 the tank, a stem for the cock extending above the tank and being jointed below the cover seat, the length of the stem above the joint being greater than the distance from the joint to the side of the tank opening

and less than the distance from the joint to 20 the end of the tank opening, the valve and stem being so related that the valve is closed when the stem folds lengthwise of the tank opening, the stem having a laterally projecting grip-piece so disposed that it is 25 transverse to the tank opening when the valve is closed.

4. In a car, in combination, a tank, a cover for the tank, a drain cock for the tank, a jointed stem for the drain cock projecting above the tank and adapted to fold below the cover seat, such stem having a lateral grip so disposed as to lie flat under the cover when the valve is closed.

HERMAN PRIES.
